C. P. ARTHUR.
BANANA CARRIER.
APPLICATION FILED JULY 22, 1916.

1,229,205.

Patented June 12, 1917.

By Watson E. Coleman

Attorney

UNITED STATES PATENT OFFICE.

CHARLES P. ARTHUR, OF HAMPTON, IOWA.

BANANA-CARRIER.

1,229,205.

Specification of Letters Patent. Patented June 12, 1917.

Application filed July 22, 1916. Serial No. 110,719.

To all whom it may concern:

Be it known that I, CHARLES P. ARTHUR, a citizen of the United States, residing at Hampton, in the county of Franklin and 5 State of Iowa, have invented certain new and useful Improvements in Banana-Carriers, of which the following is a specification, reference being had to the accompanying drawings.

10 This invention comprehends certain new and useful improvements in banana-carriers or holders, and it has for its primary object a very durable and efficient construction of device of this character in which a bunch 15 of bananas may be very easily placed and effectively suspended and be protected from flies and other insects, while at the same time access may be easily had, whenever desired, to the interior of the casing forming part of 20 the holder, so that any desired number or "hands" of bananas may be cut off.

And the invention also aims to generally improve devices of this class so as to render them more useful and commercially desirable.

With these and other objects in view, as will more fully appear as the description proceeds, the invention consists in certain constructions, arrangements and combinations of the parts that I shall hereinafter more fully describe and claim.

For a full understanding of the invention, reference is to be had to the following description, and accompanying drawing, in 35 which,

Figure 1 is a vertical longitudinal sectional view of a banana carrier or holder constructed in accordance with my invention,

40 Fig. 2 is a side elevation thereof, the lower part being broken away,

Fig. 3 is a horizontal section on the line 3—3 of Fig. 2,

45 Fig. 4 is a fragmentary sectional view showing one of the latches and keepers for holding the detachable bottom in place, and

Fig. 5 is a top plan view thereof.

Corresponding and like parts are referred to in the following description and designated in the accompanying drawing by like reference characters.

My improved banana carrier or holder comprises a preferably circular base 1 from which any desired number of legs 2 arise, 55 said legs being three in number in the pres-

ent instance, and curving slightly upward and inward, as shown, and designed to support the preferably cylindrical casing 3 of the device, the body of said casing being formed of wire mesh or galvanized screen 60 so that air and light may find access to the bunch of bananas suspended in the casing while at the same time the bananas will be protected from flies and other insects.

The casing 3, in addition to its galvanized screen body portion, is composed of any desired number of upright bars 4, preferably of bright tin or other metal and any desired number of horizontally disposed bands 5, and the main cylindrical part of the casing 70 is surmounted by a preferably dome-shaped top 6 provided at its apex with a knob 7 which is formed with a depending hook 8. The hook 8 is intended to support a block and tackle 9, the traveling sheave 10 of 75 which is formed with a hook 11, adapted to directly support a bunch of bananas by being engaged with a loop of twine or the like tied to the stem of the bunch, whereby the bunch of bananas may be readily inserted 80 in between the legs 2 and up through the lower end of the casing 3 and suspended within the latter.

The casing 3 is formed with a door or movable section 12, as clearly illustrated in 85 the drawing, said door being hinged at 13, and provided with a latch 14 of any desired construction or design to hold it in closed position.

The bottom 15 of the casing 3 is also 90 formed of wire mesh or galvanized screen material and is detachable. In the present instance, it is provided with a metallic band 16 on which any desired number of latches 17 are mounted, said latches being preferably spring-pressed latches and provided with rearwardly extending finger pieces 18, and with beveled hooks 19 designed to engage with beveled keepers 20, whereby, when the bottom is inserted upwardly into the 95 lower end of the casing, the latches 17 will spring past and subsequently engage the keepers 20 and hold the bottom securely in place. Thus the bunch of bananas will be entirely housed and protected. The bottom 100 may be very readily removed whenever desired, by merely pressing the latches 17 backward and releasing the hooks thereof from the keepers 20. Preferably the keepers 20 are formed of metal strips doubled 105 110

upon themselves at one end, as at 21, so as to hook over and engage and be secured to the lowermost band 5 of the casing 3.

From the foregoing description in connection with the accompanying drawing, the operation of my improved banana holder or carrier will be apparent. In the practical use of the device, after the bottom 15 of the casing is removed, the bunch of bananas is engaged with the hook 11 and drawn upwardly into the casing 3, whereupon the bottom is replaced. Whenever it is desired to cut off any number of bananas this can be very readily done by first opening the door 12.

While the accompanying drawing illustrates what I believe to be the preferred embodiment of my invention, it is to be understood that the invention is not limited thereto but that various changes may be made in the construction, arrangements and proportions of the parts without departing from the scope of the invention as defined in the appended claims.

What is claimed, is:

1. A banana carrier, comprising a casing provided with a lower open end and a side opening door, a bottom insertible within the lower end of the casing, the casing being provided at its lower end with a band, keepers having hooked ends engaging over the upper edge of said band, and latches carried

by the bottom and engageable with said keepers whereby the bottom may be detachably held within the lower end of the casing. 35

2. A banana carrier, comprising a foraminous casing provided with a lower open end and a side opening door, a bottom of foraminous material insertible within the lower end of the casing, the casing embodying bands, 40 one of which is at the lower end of the casing, keepers having hooked ends engaging over the upper edge of the lowermost band, and latches carried by the bottom and engageable with said keepers whereby the bottom may be detachably held within the 45 lower end of the casing.

3. A banana carrier, comprising a casing provided with a lower open end and a side opening door, a bottom insertible within the 50 lower end of the casing and embodying a band, latches carried by said band, and keepers carried by the casing at the lower end of the latter and formed with beveled hooks engageable with said latches, whereby the bottom may be detachably held within the lower 55 end of the casing.

In testimony whereof I hereunto affix my signature in the presence of two witnesses.

CHARLES P. ARTHUR.

Witnesses:

C. F. MEIER,
ALBIN JOHNSON.
